UNITED STATES PATENT OFFICE.

CORNELIUS B. CORCORAN, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,264,160.

Specification of Letters Patent. Patented Apr. 30, 1918.

Application filed November 29, 1916. Serial No. 134,028.

To all whom it may concern:

Be it known that I, CORNELIUS B. CORCORAN, a citizen of the United States, residing in borough of the Bronx, in the county of the Bronx, city and State of New York, have invented certain new and useful Improvements in Type-Writing Machines, of which the following is a specification.

This invention relates to line-spacing mechanism for typewriting machines, and more particularly to devices for rotating the platen a fraction of the regular line-space, either forwardly or rearwardly, to enable characters to be written above or below the printing line, and also to enable the writing of numerators and denominators.

I provide an improved and simplified device for this purpose, comprising means which controls a pivoted platen detent, engaging with the usual line-space wheel, to rotate the platen through a fractional line-space in either direction. By simply moving a finger-piece forwardly or backwardly from normal position, the platen is set as desired.

The platen detent is pivoted on a spring-pressed plate, and normally locked against motion thereon. A finger-piece or handle is moved to unlock the detent, and then to move the detent in either of two directions, to cause the fractional line-spacing or setting of the platen.

Means is also provided, comprising, in the form of the invention herein-disclosed, a finger-piece and cam member operated thereby, for moving the detent and its support out of engaging relation with said line-space wheel to render said detent ineffective.

Other features and advantages will hereinafter appear.

In the accompanying drawings:

Figure 1 is a side elevation of the typewriter carriage as seen from the left, with the usual finger wheel removed, the platen-rotating devices being in their normal positions.

Fig. 2 is a fragmentary side elevation of the typewriter carriage, looking in the same direction as in Fig. 1, and shows the operating handle moved, to effect a fractional line-space of the platen, to permit printing of exponents and numerators of fractions on the work-sheet.

Fig. 3 is a view similar to Fig. 2, except that the finger-piece has been moved in op-

posite direction to rotate the platen, to permit the printing of subscripts and denominators of fractions on the work-sheet.

Fig. 4 is a fragmentary front elevation of the typewriter carriage, with the fractional line-space mechanism mounted thereon.

Fig. 5 is a fragmentary sectional front elevation of the fractional line-space mechanism, the section being taken substantially on the line 5—5 of Fig. 1.

Fig. 6 is a perspective view of some of the parts comprising the fractional line-space mechanism before assembling.

Fig. 7 is a fragmentary side elevation, showing the platen detent moved out of engagement with the line-space wheel, so as to render the detent ineffective.

Fig. 8 is a view of the detent-carrying element as seen from the left-hand side.

In the Underwood machine, the platen 9 on the shaft 10 is rotatably supported in a carriage comprising end plates 11, there being only one end plate shown in the drawings. To effect line-space movements of the platen, there is provided a usual line-space handle 12, which when actuated, moves a slide 13 having a line-space pawl 14, pivoted thereon, by a shoulder screw 15. The slide moves against the tension of a spring 16, the line-space pawl 14 engaging with a line-space wheel 17, secured to the platen axle 10, to rotate the platen 9. A spring-pressed detent roller 18 co-operates with the line-space wheel 17, to retain the platen in a line-space position.

The typewriting machine includes the usual type-bars 21 comprising types 22, which swing upwardly and rearwardly against the front face of the platen 9, to print through the usual ribbon (not shown), the characters 23 on a work-sheet 24, which is fed around the platen by feed rolls 25 and 26. As the typewriter carriage travels along, the types 22 print on the work-sheet 24 in a substantially straight line, unless the line-space mechanism, including the pawl 14, is operated or the platen rotated by the knob 27, which is secured to the platen axle 10 by screws 28.

To print above the usual printing line 105 which is desirable when printing exponents and numerators of fractions, I have provided a fractional line-space handle or finger-piece 30, which is swung forwardly about a shoulder screw 31 threaded into the 110

end plate 11, Fig. 5. The early part of the movement of the handle 30 is effective to disconnect the detent 18 from a detent plate 32 to which it is normally locked, by moving 5 a shiftable stud 33 on a slide 34, carried by a detent member 35, out of a notch 36, by means of a cam 37 formed by a cam slot 38, in the lower end of the finger-piece or operating lever 30. During this movement. 10 of the stud 33, the stud-carrying slide 34 is moved against the tension of a spring 39, connected at one end to the head of the stud 33, and at its other end to a pin 40 on the operating lever 30. The slide 34 moves 15 lengthwise of the detent member 35, and is guided in its movement by the stud 33, which is threaded into the slide 34 and projects through a slot 41, formed in the upper end of the detent-carrying member 35, and 20 by a shouldered screw 42 which passes through a slot 43 in the slide 34, and is threaded into the detent-carrying member 35.

A continued forward movement of the 25 handle 30, after the platen detent has been released from its support or detent plate 32, causes the detent-carrying member 35 to swing about its pivot, comprising a shouldered screw 44 which is threaded into the 30 support 32. The head of the screw passes into a hole 45 in the detent-carrying member 35, and the reduced portion 46 of the screw passes into a hole in an ear 47, (Figs. 5 and 8) bent up from the detent-carrying member 35 and around the support 32.

During the movement of the detent-carrying member 35, the detent roller 18 is moved bodily about the pivot or shoulder screw 44 and co-operates with the line-space wheel 17, 40 to rotate the platen through an angular distance, indicated by X, Fig. 2, which is equal to a fractional line-space. If a type-bar is actuated while the platen is in this position, it will print a character above the usual 45 printing line, a distance equal to the arc subtended, at the platen surface, by the angle X. While the parts are in the Fig. 2 position, the spring 39 is under increased tension but is ineffective to return the parts 50 to normal position, as long as the stud 33 is in one or the other end of the slot 43, formed in the detent plate 32.

To restore the parts to normal position, which is necessary before printing the 55 vision line of a fraction, the handle is moved toward its central or Fig. 1 position, until the stud is substantially in line with the notch 36 in the detent plate 32, when the spring 39 becomes effective to move the stud 60 33 back into the notch 36, and assist in restoring the operating handle 30.

To print below the usual printing line, which is desirable when printing subscripts or denominators of fractions, the handle 30 65 is moved rearwardly from the Fig. 1 to the

Fig. 3 position. The early part of the movement of the handle is again effective to move the stud 33 out of engagement with the detent plate 32, thereby releasing the detent-carrying member 35, after which a further movement of the operating handle is effective to rotate the platen through an angular distance indicated at Z in Fig. 3. If a type-bar is actuated while the platen is in the position indicated in Fig. 3, it would 70 print a character below the usual printing line, a distance equal to the arc at the platen surface, subtended by the angle Z. The parts will remain in this position until the operating handle is brought back to its central or normal position indicated in Fig. 1. 75

The movement of the operating handle in either direction from the Fig. 1 position is limited by the stud 33 engaging in the ends of the slot 48. 80

To render the detent roller 18 ineffective, or in other words, to move the detent roller out of engagement with the line-space wheel 17, I have pivoted a finger-piece 49 on the platen shaft 10 (Figs. 1, 4 and 7), which has a cam 50 thereon, engaging with a stud 51 on the detent-carrying member 35, to swing the detent-carrying member with its support or detent plate 32 about the pivot or shoulder screw 31, to take the detent roller 18 out of engagement with the line-space wheel 17, as indicated in Fig. 7. While moving to this position, the parts are moved against the tension of a spring 52 coiled around a cap 53, which fits over a hub 54, 90 extending laterally from the detent plate or support 32, one end of the spring being anchored by a pin 55; the other end pressing against a pin 56 on the detent plate 32. 95

It will be seen by inspection of Figs. 5 100 and 6 that the fractional line-space handle is held on its pivot by the head of the screw 31; that a shoulder 57 on the screw 31 holds the support 32 to allow rotative movement thereof; and that a shoulder 58 binds the 105 cap 53 about which the spring 52 is wound against the end plate 11. Suitable spacing washers 59 and 60 are provided to locate the mechanism the proper distance away from the end plate 11, so as to have the detent 110 roller 18 in alinement with the line-space wheel 17.

Variations may be resorted to within the scope of the invention, and portions of the improvements may be used without others. 115

Having thus described my invention, I claim:

1. In a typewriting machine having a platen and regular line-space mechanism therefor, including a line-space wheel, a 120 fractional line-space mechanism comprising, in combination, a movably mounted detent support, a swinging detent pivoted to said support, means normally opposing relative movement between said detent and its sup- 125

port, means for moving said detent and its support as a unit, said means serving to yieldingly hold said detent in engagement with said line-space wheel, and means, including a movably mounted finger-piece for causing a movement of said detent relative to its supporting member and in a direction such as to effect a line-space movement of said line-space wheel and platen.

10 2. In a typewriting machine having a platen and regular line-space mechanism therefor, including a line-space wheel, a fractional line-space mechanism comprising, in combination, a pivoted detent support, a 15 detent for said line-space wheel movably mounted upon said support, means normally opposing relative movement between said detent and its support, a spring tending to rotate said detent support and its detent as 20 a unit in a direction such as to yieldingly hold said detent in engagement with said line-space wheel, said detent and its supporting member being movable as a unit against said spring when acting as a detent 25 during regular line-spacing, and means, including a movably mounted finger-piece, for causing a movement of said detent relative to its supporting member and in a direction such as to effect a line-spacing movement of 30 said line-space wheel and platen.

3. In a typewriting machine having a platen and regular line-space mechanism therefor, including a line-space wheel, a fractional line-space mechanism comprising, in combination, a movably mounted detent support, a detent for said line-space wheel movably mounted upon said support, means for normally locking said detent with respect to said support to prevent relative 40 movement of one with respect to the other, means for moving said detent and its support as a unit and for holding said detent in yielding engagement with said line-space wheel, and a finger-piece movably mounted 45 on said detent support and provided with means for first rendering said locking means ineffective, and then causing a movement of said detent relative to its support and in a direction such as to effect a line-space movement 50 of said line-space wheel and platen.

4. In a typewriting machine, the combination with a platen and regular line-spacing mechanism comprising a line-space wheel, of a fractional line-space mechanism comprising a manually controlled cam member, a platen detent, a detent plate, and a movable stud carried by said platen detent and engaging with said detent plate, said cam member being effective to disengage 55 said stud from said detent plate and to effect a fractional line-space of the platen.

5. In a typewriting machine having a platen and regular line-space mechanism therefor, including a line-space wheel, a fractional line-space mechanism comprising,

in combination, a movably mounted detent support, a detent for said line-space wheel movably mounted on said support, means normally opposing relative movement between said detent and its support, means for 70 moving said detent and its support as a unit and for holding said detent in yielding engagement with said line-space wheel, means, including a movably mounted finger-piece, for causing a movement of said detent relative to its support and in a direction such as to effect a line-space movement of said line-space wheel and platen, and engaging means between said detent and its support for limiting relative movement thereof in accordance with the extent of line-space movement 75 to be effected.

6. In a typewriting machine having a platen and regular line-space mechanism therefor, including a line-space wheel, a fractional line-space mechanism comprising, in combination, a movably mounted detent support, a detent for said line-space wheel movably mounted on said support, means normally opposing relative movement between 80 said detent and its support, means for moving said detent and its support as a unit, said means serving to yieldingly hold said detent in engagement with said line-space wheel, and means, including a movably mounted finger-piece, for causing a movement of said detent relative to its supporting member and in a direction such as to effect a line-space movement of 85 said line-space wheel and platen.

7. In a typewriting machine having a platen and regular line-space mechanism therefor, including a line-space wheel, a fractional line-space mechanism comprising, in combination, a movably mounted detent support provided with a lock-notch and a stop surface, a detent for said line-space wheel movably mounted on said support, said detent having a slot therein, a movably mounted stud normally engaging said slot 100 and lock-notch to prevent relative movement between said detent and its support, resilient means acting on said detent support to hold said detent in yielding engagement with said line-space wheel, and a movably mounted finger-piece having a cam for 105 engaging said stud and effective, on first movement of said finger-piece, to move said stud out of said lock-notch, and on further movement of said finger-piece, to move said 110 detent relatively to its support, in a direction such as to effect a line-space movement of said line-space wheel and platen, the extent of such line-space movement being limited by engagement of said stud with 115 said stop surface.

8. In a typewriting machine, the combination with a platen and regular line-spacing mechanism, of a fractional line-space mechanism comprising a finger-piece, a pivoted

platen detent, and a support for said platen detent to which the latter is normally locked, said finger-piece being effective to unlock said platen detent from its support, 5 and to move said platen detent about its pivot to effect a fractional line-space of the platen.

9. In a typewriting machine, the combination with a platen and regular line-spacing 10 mechanism comprising a line-space wheel, of a fractional line-space mechanism comprising a detent plate, a finger-piece, a cam controlled by said finger-piece, a platen detent, and a stud on said platen detent normally 15 in engagement with said detent plate, said finger-piece when moved, being effective; first, to disengage said stud from said detent plate, and then to move said platen detent to cause a fractional line-space of the 20 platen.

10. In a typewriting machine, the combination with a platen and regular line-spacing mechanism, of a fractional line-space mechanism, comprising a platen detent element, a movable element, supported 25 by said platen detent, comprising a lock for said platen detent, and means for releasing said platen detent and for moving it to effect a fractional line-space of the platen.

11. In a typewriting machine, the combination with a platen and regular line-spacing mechanism, of a fractional line-space mechanism, comprising a platen detent, a plate on which said platen detent is 30 movably supported, means for locking said detent to said plate, and means for actuating said locking means to release said detent from said plate to effect a fractional line-space of the platen.

12. In a typewriting machine, the combination with a platen and regular line-spacing mechanism, comprising a line-space wheel, of a fractional line-space mechanism, comprising a pivoted platen detent, a 35 slide supported by said platen detent, a support on which said platen detent is pivoted, said slide engaging with said support to lock said detent against movement on its pivot, and a finger-piece engaging with said 40 slide to unlock said detent from its support, and then rotate the platen a fractional line-space.

13. In a typewriting machine having a platen and regular line-space mechanism therefor, including a line-space wheel, a 55 fractional line-space mechanism comprising, in combination, a movably mounted detent support, a detent for said line-space wheel movably mounted on said support, means for normally opposing a relative 60 movement between said detent and its support, resilient means for moving said detent support and its detent as a unit and for holding said detent in yielding engagement 65 with said line-space wheel, means including a movably mounted finger-piece for causing movement of said detent relative to its support and in a direction such as to effect a line-space movement of said line-space wheel and platen, and means for moving 70 said detent and its support as a unit, against the action of said resilient means, out of engagement with said line-space wheel to render said detent ineffective.

14. In a typewriting machine having a 75 platen and regular line-space mechanism therefor, including a line-space wheel, a fractional line-space mechanism comprising, in combination, a movably mounted detent support, a detent for said line-space 80 wheel movably mounted on said support, means for locking said detent to its support to prevent relative movement thereof, a spring for moving said detent and its support as a unit, said spring serving as means 85 for yieldingly holding said detent in engagement with said line-space wheel, a finger-piece movably mounted on said detent support and provided with means for first rendering said locking means ineffective, 90 and for subsequently causing a movement of said detent relative to its support in a direction such as to effect a line-space movement of said line-space wheel and platen, and means, including a cam member, for 95 moving said detent and its support as a unit against the action of said spring, thus moving said detent out of engagement with said line-space wheel to render said detent ineffective.
